(57) **CLAIM**

The ornamental design for a gripping attachment apparatus, as shown and described.

DESCRIPTION

FIG. 1 is a front perspective view of our design for a gripping attachment apparatus;

FIG. 2 is a back perspective view thereof;

FIG. 3 is a top plan view thereof;

FIG. 4 is a bottom plan view thereof;

FIG. 5 is a front elevation view thereof; and,

FIG. 6 is a right view thereof.

The back side is a mirror image to the front side.

The left side is a mirror image to the right side.

In the drawings, the broken lines are for the purpose of illustrating environment only and form no part of the claimed design.
